Primary Examiner — Michelle E. Wilson*Assistant Examiner* — Clese Moore, Jr.(74) *Attorney, Agent, or Firm* — Rothwell, Figg, Ernst & Manbeck, P.C.(57) **CLAIM**

The ornamental design for a gown, as shown and described.

DESCRIPTION

FIG. 1 is a front left side perspective view of a gown;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front view of the gown with two panels of the gown separated to show two straps thereof.

The portions of the gown shown in broken lines form no part of the claimed design.

1 Claim, 6 Drawing Sheets(56)
